IGNITION CONTROL SYSTEM

Richard Steensma, Fair Lawn, N. J., assignor to
Wright Aeronautical Corporation, a corpora-
tion of New York

Application March 11, 1947, Serial No. 733,805

8 Claims. (Cl. 315—246)

1

This invention relates to ignition control systems for burners and is more particularly directed to an ignition control system for a burner in which the burner igniter means is automatically rendered operative upon extinction of the burner flame.

Gas turbine and jet engines operate with a large amount of excess air which flows over the burner nozzles at high velocity. Accordingly, there is danger of the combustion flame being blown out or otherwise extinguished as a result of changes in engine operating conditions as, for example, changes in the air velocity, temperature or pressure and/or changes in the rate of fuel supply. This combustion difficulty is particularly present in engines designed for aircraft use because such engines operate under a wide range of conditions which may change quite suddenly.

A primary object of the invention comprises the provision of means associated with a burner for automatically reigniting the combustion mixture should the combustion flame become extinguished. Although the invention is of general application, it has been designed for use with aircraft engines and, accordingly, the system preferably should be simple, quite rugged and capable of operating at high temperatures.

Specifically the invention comprises an ignition control system including one or more pairs of spaced electrodes disposed in the path of the combustion flame, the increase in impedance across said electrodes, upon extinction of the combustion flame, being effective to render suitable burner igniter means operative as long as said flame remains extinguished. When said flame is re-established, the decrease in impedance across said electrodes is effective to render said igniter means inoperative.

Other objects of the invention will become apparent upon reading the annexed detailed description in connection with the drawing in which:

Figure 1 is a diagrammatic view disclosing the combustion igniter control means of the present invention; and

Figure 2 is a partial view of a modified form of the invention.

Referring first to Figure 1 of the drawing, a combustion chamber 10 is provided with a burner nozzle 12 through which a suitable fuel, supplied from a conduit 14, is sprayed into the combustion chamber 10. Air is supplied through the annular passage 16 about the burner nozzle for combustion with the fuel sprayed from said nozzle. In order to ignite the fuel and air, one or

2

more spark plugs 18 are disposed in the flow path of the combustion mixture. For this purpose, and as hereinafter described, the spark plug or plugs 18 are connected in a circuit which, when closed, produces a series of sparks across the electrodes of the plug 18 for igniting the combustion mixture, said sparks continuing until combustion has been established or re-established. As will appear, the specific construction of the combustion chamber, the burner and the igniter therefor form no part of the present invention.

One or more pairs of spaced electrodes 20 and 22 are disposed in the combustion chamber 10 for detecting the presence or absence of the combustion flame therein. These electrodes may comprise the electrodes of a conventional spark plug. Preferably, however, one of the electrodes 20 comprises a central insulated electrode of a plug-like member 24 while the adjacent grounded 15 wall of the combustion chamber 10 or the grounded outer sleeve of the plug-like member 24 forms the other electrode 22. The distance between the electrodes 20 and 22 of the flame detectors 24 is not critical; however, it is essential that the gap between these electrodes lie in the path of the burner flame 23. The flame detecting devices 24 are disposed at different locations relative to the burner nozzle in order that the electrodes of at least one said device 24 are disposed in the burner flame regardless of the length 20 of the flame. For example, with two flame detecting devices 24, the one is disposed relatively close to the burner nozzle in order to detect a short flame at low rates of fuel supply, but this flame detector may not be in the path of the flame at high rates of fuel flow. Accordingly, the other flame detector 24 is disposed at some distance from the burner nozzle in order to detect a relatively long burner flame, as exists at high 25 rates of fuel supply.

The ignition circuit for the spark plug 18 is conventional. As illustrated, the spark plug 18 is connected across the high tension winding of a transformer 30 while the low tension winding of 45 said transformer is connected in series with conventional vibrator means 32, a battery 34, a switch 35 and a small resistance 36 to a pair of contacts 38. The contacts 38 are controlled by a switch arm 42 of a relay 44. The relay arm 42 is biased to its position bridging the contacts 38, for example by a spring 45. A condenser 40 is connected across the contacts 38 to minimize arcing when the switch arm 42 breaks the ignition circuit at said contacts. The particular form of igniter for the burner 12 forms no part of the pres-

55

ent invention, in fact, as mentioned, the spark plug igniter 18 and the ignition circuit therefor is conventional. The invention is primarily directed to means for controlling the relay 44 or an equivalent device so as to automatically render the combustion igniter means operative when the combustion flame is extinguished. Accordingly, the provision of any suitable igniter under the control of the relay 44 or under the control of an equivalent device is within the scope of the invention.

With the ignition circuit and igniter means illustrated, after the switch 35 has been closed and when the relay switch arm 42 bridges the contacts 38, the vibrator 32 operates to make and break the primary circuit of the transformer 30 whereby as long as the switches 35 and 42 remain closed, a series of sparks is produced across the electrodes of the igniter plug 18 for igniting the combustion mixture. By opening the switch 35 the operator can render the igniter inoperative when the burner is shut down. An indicator lamp 45 is connected across the resistance 36 whereby the lamp 45 is energized whenever the igniter is operative thereby informing the operator of this fact. In addition means may be provided so that the operator can render the igniter operative independently of the relay 44. For this purpose a normally open switch 46 may be connected in parallel with said relay.

The relay 44 and the control apparatus therefor preferably is housed in a grounded metal container schematically indicated at 47. An alternating current source of electric power 48 is supplied to said control apparatus through power terminals 50 and 52 and a switch 54, the terminal 50 and the metal container 47 being grounded as indicated at 56. A pair of resistances 58 and 60 are serially connected across the terminals 50 and 52 to form two arms of a bridge circuit. A resistance 62 forms the third arm of said bridge circuit and the flame detecting electrodes 20 and 22 are included in the fourth arm of said bridge circuit. The outer end 63 of each insulated electrode 20 is connected to a wire lead 64 which leads are joined to a common lead 65 extending into the container 47 for connection to one end of the resistance 62 preferably through a rectifier 66. For this purpose the wire lead 65 is connected to the plates or anodes 68 of the rectifier tube 66 and a wire 70 connects the cathodes 72 of the tube 66 to one end of the resistance 62. The return circuit to the electrode 22 comprises a ground return through a metallic shield 73 disposed about the wire leads 64 and 65. The shield 73 is connected at one end to the grounded metal container 47 and at the other end to the grounded metal wall of the combustion chamber 10 forming the grounded electrodes 22. The other end of the resistance 62 is connected to a contact 74 adjustable along the resistance 60.

With this bridge circuit construction the electrodes 20 and 22 with their rectifier 66 comprise one arm of said circuit, and the resistances 58, 60 and 62 comprise the other arms of said circuit. A condenser 75 is connected in parallel with the resistance 62 to balance the electric capacitance between the wire leads 64 and 65 and the grounded shields 73, which capacitance is in parallel with the gaps between the pairs of electrodes 20 and 22.

A thyratron tube 76 is connected across the bridge circuit so that said tube "fires," that is, becomes conducting, when the resistance across at least one pair of electrodes 20 and 22 is reduced by the presence of a flame therebetween.

For this purpose the control grid 78 of the thyratron tube 76 is connected by a wire 80 to the point 81 between the bridge arm comprising the resistance 62 and the bridge arm comprising the flame detecting electrodes 20 and 22 with their rectifier 66. The cathode 82 of the thyratron tube 76 is connected by a wire 84 to the junction 86 of the resistances 58 and 60 and the thyratron tube is provided with a shield grid 88 connected to said cathode by a wire 90. The filaments or heaters 92 and 94 of the tubes 76 and 66 respectively, are connected by wires 84, 96 and 98 across the secondary or low tension winding of a transformer 100, the primary of which is connected across the terminals 50 and 52 by wires 102 and 104. The anode or plate 106 of the thyratron tube 76 is connected to the terminal 50 through the relay 44, a wire 108 and the wire 102 whereby the relay 44 is energized to open the ignition circuit at contacts 38 when the thyratron tube becomes conducting. With the afore-described arrangement, the control grid 78 and its cathode 82 are connected across the bridge circuit at the points 81 and 86 whereby the bridge circuit controls the relative electrical potential of said control grid and cathode. In addition the thyratron or gas tube 76 can be rendered conducting only when the power terminal 50 is at a positive electric potential relative to the terminal 52. During the portions of the alternating current cycle when the power terminal 50 is positive, the tube 76 is rendered conducting only when the electric potential of its control grid 78 is above a predetermined value relative to its cathode. Also during said cycle portions when the terminal 50 is positive, if there is a flame in the combustion chamber 10 at either pair of flame detecting electrodes 20 and 22, the impedance across said pair or pairs of electrodes 20 and 22 will be relatively small so that the electric potential of the control grid 78 will at least be less negative as compared to its electric potential when the impedance across both pairs of said electrodes 20 and 22 is relatively high because of the absence of a flame. Accordingly, the sizes of the condensers and resistances of the bridge circuit may be so selected, and the contact 74 so adjusted that the thyratron tube 76 is automatically rendered conducting during that portion of each cycle of the alternating current source 48 when the terminal 50 is positive and when there is a flame at either pair of flame detecting electrodes 20 and 22, and said tube is automatically rendered non-conducting in the absence of a flame at both pairs of said flame detecting electrodes. With a 110 volt alternating current power source 48, a No. 6H6 rectifier tube 66 and a No. 2D21 thyratron tube 76, the system operated satisfactorily with resistances 58 and 60 equal to 45,000 and 1000 ohms, respectively, resistance 62 equal to five megohms and condenser 75 equal to .01 microfarad. Obviously, however, the specific circuit, its voltage and its tubes, as well as the specific magnitude of its resistances and capacitances are subject to considerable variation. The large decrease in impedance across the gap between each pair of electrodes 20 and 22 in the presence of a flame is believed to be due to ionization existing in a flame.

It is a characteristic of thyratron or gas tubes that once the tube becomes conducting, the tube remains conducting and the grid loses control until the tube plate voltage falls below that required to maintain ionization within the tube 76.

If the plate voltage of a thyratron tube is pe-

riodically decreased sufficiently to render the tube non-conducting for a short length of time its grid immediately regains control each time the plate voltage is so reduced. For this reason, the plate circuit of the thyratron tube 76 is connected to an alternating current power source 48. With this arrangement, during each portion of the alternating current cycle that the power terminal 50 is positive, the plate voltage of the tube 76 will be above that required to maintain the tube conducting so that if the potential of the control grid 78 is sufficiently high during said cycle portions, the tube 76 will be conducting during each said cycle portion. Accordingly, as long as a combustion flame continues to exist in the combustion chamber 10, the tube 76 will fire (become conducting), during each cycle portion that the power terminal 50 is positive, thereby rendering the igniter 18 inoperative by energizing the relay 44 to open the contacts 38.

If the combustion flame becomes extinguished for any reason, the tube 76 will become non-conducting during the next cycle portion that the power terminal 50 is negative and the tube will remain non-conducting as long as the combustion flame is extinguished thereby de-energizing the relay 44 whereupon the relay switch arm 42 bridges its switch contacts 38 to render the igniter 18 operative (switch 35 having been closed in starting the burner). Thus, a series of sparks is produced by the igniter plug 18 until a flame has been established in the combustion chamber 10 at which time the relay 44 is again energized as described to open the ignition circuit at the contacts 38 thereby rendering the igniter 18 inoperative. Similarly, in starting the burner, when the switches 35 and 54 are closed, a series of sparks is produced by the igniter plug 18 until a combustion flame has been established. The output of the thyratron tube 76 is a pulsating unidirectional current so that the arm 42 of the relay 44 may tend to chatter against its contacts when said relay is energized by this current. To prevent this possibility a condenser 110 is connected in parallel with the relay 44.

Because of the grounded shielding 73 about the wire leads 64 and 65 there is considerable electric capacitance between said leads and shielding, which capacitance is in parallel with the electrodes 20 and 22. The impedance of this capacitance is quite low when an alternating current voltage is impressed across the electrodes 20 and 22 and therefore with such an alternating current voltage, the impedance of the arm of the bridge circuit including said electrodes would be quite low even in the absence of a flame between said electrodes. However, when the rectifier 66 is connected in series with the electrodes 20 and 22 a pulsating direct current voltage is applied across said electrodes, thereby greatly increasing the aforementioned impedance in parallel with the said electrodes. Accordingly with the rectifier tube 66 in series with the electrodes 20 and 22 there is a larger increase in the impedance in this arm of the bridge circuit when the flame between both pairs of electrodes 20 and 22 is extinguished as compared to the increase which would take place in the absence of said rectifier. Therefore, the presence of the rectifier 66 greatly increases the sensitivity of the bridge circuit. In fact without the rectifier 66 and with the resistance 62 equal to approximately 5 megohms the thyratron tube 76 remained conducting regardless of the presence or absence of a flame between the electrodes 20 and 22. In addition because the im-

pedance of the capacitance between the wire leads 64 and 65 and the grounded shield 73 is large with the rectifier 66 connected into the bridge circuit, the bridge circuit control of the thyratron tube 76 is substantially independent of the length of said wire leads.

The rectifier tube 66 has been illustrated as a twin diode-type tube. However, as connected in the circuit, the tube 66 only acts as a half-wave rectifier so that a simple diode may be substituted therefor.

With the aforementioned control system, the presence of a combustion flame is effective to cause energization of the relay 44 to render the igniter inoperative and upon extinction of the combustion flame the relay 44 is de-energized whereupon the igniter becomes operative. With this arrangement, if some portion of the system should fail, the worst that probably would happen is that the relay 44 would become or remain de-energized whereby the igniter would be operative even though the combustion mixture may be burning in the chamber 10. Obviously, however, if desired the system may be reversed to the extent that the presence of a combustion flame would be effective to de-energize the relay 44 thereby rendering the igniter inoperative and upon extinction of the combustion flame the relay 44 would be energized to render the igniter operative.

As illustrated in Figure 1 two flame detecting devices 24 are disposed in the path of the flame from one burner 12 and these devices are connected in parallel whereby the igniter 18 is rendered operative only when there is no flame at both flame detecting devices 24. It also may be desirable to connect a plurality of flame detecting devices in series. Such an arrangement is illustrated in Figure 2 wherein like but primed reference numerals have been used to designate parts corresponding to similar parts of Figure 1.

Figure 2 discloses a plurality of individual burners 12' which may be disposed in a common combustion chamber or as illustrated in separate combustion chambers 10'. In Figure 2 the combustion chambers 10' are illustrated in transverse section instead of in longitudinal section as in Figure 1. A flame detecting device 24' and an igniter plug 18' are provided for each burner 12'. Each flame detecting device 24' differs from the corresponding device 24 of Figure 1 in that both electrodes 20' and 22' are insulated from the walls of their associated combustion chamber. Also as illustrated the gaps between said pairs of electrodes 20' and 22' are connected in series, instead of in parallel, to wires 65' and 73' leading to a control system similar to that of Figure 1. In addition in Figure 2 the igniters 18' are connected to individual step-up transformers 30' controlled by a relay 44' of the control circuit. In Figure 2 since the flame detecting electrode gaps are connected in series, the thyratron tube of the control circuit will remain conducting only as long as a flame is present at both pairs of electrodes 20' and 22'. If the combustion flame of either burner 12' becomes extinguished, the combined impedance of the serially connected gaps of the electrodes 20' and 22' will affect the bridge control circuit so as to render its thyratron tube non-conducting whereupon both igniters 18' are rendered operative until both burners 12' are again operating. One or more flame detecting devices may be connected in parallel with each device 24' in order that each burner 12' be provided with a plurality of parallel connected flame de-

tecting devices arranged, as in Figure 1, so that at least one flame detecting device of each burner is in the path of the burner flame regardless of the magnitude of said flame.

The use of a thyratron tube in the control circuit has the advantage in that as soon as the tube is rendered conducting, sufficient current flows through the tube to operate the relay 44. This is so since it is a characteristic of a thyratron tube that its control grid acts as a trigger in controlling the firing of the tube. That is, as soon as the electric potential of the thyratron control grid becomes sufficiently high a relatively large plate current flows through the tube, the magnitude of which is independent of the specific electric potential of the control grid. This advantage of a thyratron tube results from its gas atmosphere. Accordingly as used in the claims the term "thyratron tube" is intended to be broad enough to cover equivalent forms of gas filled tubes as distinguished from so-called vacuum tubes. However, it should be obvious that other forms of electronic tubes or other electric relays may be substituted for a thyratron tube.

As used in this specification and appended claims the term impedance is a general term meaning resistance to electric current flow regardless of the nature of the current.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim:

1. Flame detecting apparatus for a burner comprising a pair of spaced electrodes arranged to be disposed in the path of the burner flame; a conductor connected to one of said electrodes; a grounded metallic shield surrounding said conductor and connected to the other of said electrodes; a source of alternating current; a rectifier; an electric circuit including said source of alternating current, said rectifier, said conductor, said grounded shield and said electrodes with said conductor connected to one side of said source through said rectifier and with the other side of said source connected to ground; and an electric relay electrically connected to said circuit, said relay being operable in response to changes in the electric impedance across the gap between said electrodes such that said relay is operable to a first condition as a result of the presence of a flame at said electrodes and is operable to a second condition in the absence of said flame.

2. Flame detecting apparatus for a burner comprising a pair of spaced electrodes arranged to be disposed in the path of the burner flame; a pair of conductors each connected to one of said electrodes; an electric bridge circuit comprising four arms connected together to form a closed network with a terminal at the junction of each pair of said arms; an alternating current source of power connected to a pair of opposite terminals of said bridge; a rectifier connected in series with said electrodes and conductors at the end of one of said conductors remote from its electrode; said rectifier, conductors and electrodes constituting one arm of said bridge circuit; and a thyratron tube having its cathode connected to one of the other terminals of said bridge and having its control grid connected to the remain-

ing terminal of said bridge such that said tube is responsive to changes in the electric impedance across said gap, as a result of the presence or absence of a flame at said electrodes, for detecting the presence or absence of said flame.

5. Flame detecting apparatus for a burner comprising two pairs of spaced electrodes, said two pairs of electrodes being electrically connected in parallel and being disposed at spaced points 10 so that one pair of said two pairs of electrodes is disposed in the path of the burner flame when said flame is relatively short and the other pair of said two pairs of electrodes is disposed in the path of the burner flame when said flame is relatively long; an electric circuit connected to said parallel connected electrodes; and an electric relay operatively controlled by said circuit so as to be responsive to changes in the combined electric impedance of the parallel connected gaps 15 between said pairs of electrodes, said relay being operable to a first condition as a result of the presence of a flame at either of said two pairs of electrodes and being operable to a second condition in the absence of a flame at both of said two pairs of electrodes.

4. Flame detecting apparatus for a burner comprising a pair of spaced electrodes arranged to be disposed in the path of the burner flame; a pair of conductors each connected to one of said electrodes; a source of alternating current; a rectifier; an electric circuit including said source of alternating current, said rectifier, said conductors and said electrodes with one of said conductors connected to one side of said source and 20 with the rectifier interposed between the connection of the other of said conductors to the other side of said source; and an electric relay electrically connected to said circuit, said relay being operable in response to changes in the electric impedance in that portion of said circuit including said conductors and electrodes, as a result of the presence or absence of a flame at said electrodes, for detecting the presence or absence of said flame.

45. Flame detecting apparatus as recited in claim 4 in which one of said conductors constitutes a grounded shield for the other of said conductors.

50. Flame detecting apparatus as recited in claim 4 in which said electric circuit constitutes a bridge circuit with said rectifier, said electrodes and said conductors forming one arm of said bridge circuit.

55. Flame detecting apparatus for a burner comprising a pair of spaced electrodes arranged to be disposed in the path of the burner flame; a pair of side-by-side conductors each connected to one of said electrodes; a source of alternating current; a rectifier; an electric circuit including 60 said source of alternating current, said rectifier, said conductors and said electrodes with one of said conductors connected to one side of said source and with the rectifier interposed between the connection of the other of said conductors 65 and the other side of said source; and an electron tube electrically connected to said circuit such that variations in the electric impedance in that portion of said circuit including said conductors and electrodes, as a result of the presence or absence of a flame at said electrodes, varies the output of said tube for detecting the presence or absence of said flame.

70. Flame detecting apparatus for a burner comprising two pairs of spaced electrodes; a pair of conductors, said two pairs of electrodes being

electrically connected in parallel to said conductors and being disposed at spaced points so that one pair of said two pairs of electrodes is disposed in the path of the burner flame when said flame is relatively short and the other pair of said two pairs of electrodes is disposed in the path of the burner flame when said flame is relatively long; a source of alternating current; a rectifier; an electric circuit including said source of alternating current, said rectifier, said conductors and said electrodes with one of said conductors connected to one side of said source and with the rectifier interposed between the connection of the other of said conductors to the other side of said source; and an electric relay electrically connected to said circuit, said relay being operable in response to changes in the electric impedance in that portion of said circuit including said conductors and said parallel connected pairs of electrodes such that said relay is operable to a first condition as a result of the presence of a flame at either of said two pairs of electrodes

and is operable to a second condition in the absence of a flame at both of said two pairs of electrodes.
